DESIGN FOR A COMBINED KNIFE AND TOWEL RACK

Jacob M. Marateck, Bronx, N. Y.

Application November 22, 1944, Serial No. 116,496

Term of patent 7 years

(Cl. D33—16)

To all whom it may concern:

Be it known that I, Jacob M. Marateck, a citizen of the United States and resident of the Borough of Bronx, county of Bronx, city and State of New York, have invented a new, original, and ornamental Design for a Combined Knife and Towel Rack, of which the following is a specification, reference being had to the accompanying drawing, forming part thereof, in which

Fig. 1 of the drawing is a view in perspective of the combined knife and towel rack embodying my design; and

Fig. 2 of the drawing is an edge view of the same.

What I claim is:

The ornamental design for a combined knife and towel rack, substantially as shown.
